(57) **CLAIM**

I claim the ornamental design for a dual prayer pillow, as shown and described.

DESCRIPTION

FIG. 1 is a perspective view of the dual prayer pillow;

FIG. 2 is a top view thereof;

FIG. 3 is a bottom view thereof;

FIG. 4 is a front elevational view thereof;

FIG. 5 is a rear elevational view thereof;

FIG. 6 is a right elevational view thereof; and,

FIG. 7 is a left elevational view thereof.

The broken lines are for environmental purposes only and form no part of the claimed design.
